NONREFILLABLE CLOSURE FOR BOTTLES
AND OTHER CONTAINERSGilbert Jackson, New York, N. Y., and Joseph
F. Maher, Ridgefield Park, N. J.

Application October 3, 1936, Serial No. 103,810

1 Claim. (Cl. 215—22)

This invention relates to closures and it particularly relates to nonrefillable closures for bottles and similar liquid containing receptacles.

In Patent No. 1,348,116, dated July 27, 1920 and in the co-pending applications, Serial No. 697,892, filed November 1, 1933, and Serial No. 742,696, filed September 4, 1934, there are disclosed nonrefillable bottle closures or caps, which have for their objects, the prevention of the refilling of bottles after they had been emptied.

In said patent and applications, there are disclosed hollow valve members, which are enclosed in and cooperate with a valve seat casing member inserted into the mouths of bottles. Above the valves are positioned locking balls, the balls being confined between the valve members on one side, and concave contact members at the other.

In these closures, as well as other types of closures, with change in temperature, as when the bottles provided with the closures are taken from indoors to outdoors in winter, or are moved from a warm place to a cool place, either indoors or outdoors, there are times when the vapors or air above the liquid in the bottle will tend to condense or contract resulting in the creation of a partial vacuum.

This makes pouring rather difficult, as such a vacuum will tend to hold the valve closed, even against the weight of the liquid in the inverted bottle.

An object of the present invention is to provide a nonrefillable bottle closure of the type above described, in which the valve member and its associated parts may be most inexpensively and easily constructed from readily available materials, as for example, ceramic materials, and which will be readily operated to permit pouring, even when cooling of the bottle results in a partial vacuum.

Other objects will appear during the course of the following specification.

The essential feature of the present invention resides in the provision of breathing openings in the closure structure, permitting passage of vapors to the interior of the bottle from the atmosphere when partial vacuums are created, but preventing passage of liquid.

These passageways may be most conveniently formed in a ceramic valve material, by inserting thin flexible wires or needles into the ceramic material when molded or formed and still soft, and before firing and vitrification.

The needles or wires should preferably be of such resiliency as to be deflected by harder particles in the ceramic and follow an irregular path

through such ceramic. This sort of a passage will more readily tend to block liquid passage, while permitting gaseous flow.

It has been found most suitable in one embodiment to provide a valve casing having an upper portion, exteriorly exposed, and a lower portion to communicate with the interior of the container or bottle.

The lower portion of the valve casing may be of a decreased diameter so as to fit conveniently into the neck of the bottle, a shoulder being preferably provided on the casing to limit insertion thereof.

Interiorly positioned in the lower portion of the valve casing is a valve member, the lower end of which valve member is conformed so as to cooperate with a valve seat interiorly formed in the bottom of the casing adjacent the interior opening thereof above described.

The lower portion of the casing is preferably provided with the breathing openings in the side walls thereof above the valve seat.

In the accompanying drawing in which are shown one or more of various possible embodiments of the several features of the invention,

Fig. 1 is a longitudinal cross sectional view of the nonrefillable valve device of the invention on a bottle top;

Fig. 2 is a transverse sectional view upon the line 2—2 of Fig. 1;

Fig. 3 is a transverse sectional view upon the line 3—3 of Fig. 1;

Fig. 4 is a top view of the conical portion at the top of the movable valve;

Fig. 5 is a bottom view of the valve structure;

Fig. 6 is a top perspective view of the hollow valve member with its cover portion removed;

Fig. 7 is a diagrammatic sectional view upon an enlarged scale showing one of the bleeder or breathing passageways;

Figs. 8 and 9 are side sectional and elevational views respectively illustrating how the valve casing and the valve structure are handled and supported during firing.

Referring to Fig. 1, the bottle or other container B is provided with a cylindrical mouth 10. The bottle is adapted to receive alcoholic beverages or any other liquid to be dispensed. The upper exposed cylindrical valve casing member 12 is provided with a lower cylindrical insert portion 13 of reduced diameter, which is inserted in the opening 10 in the mouth or neck of the bottle B, preferably with a slight clearance.

The lower insert portion 13 is provided with a flange 8 at its upper end, which fits into the

shoulder 9 on the interior of the upper casing section 12. The upper section 12 and the lower section 13 are held together by sealing wax 7, which is preferably of a material not affected by 5 alcoholic beverages or other liquids which may be contained in the bottle B.

It is noted that the shoulder 9 is enlarged at 6 to receive the sealing wax body 7. The upper casing 12 is provided with an exterior flange or 10 peripheral extension 14 which cooperates with a corresponding projection 15 on the bottle. The flange 14 and the flange 15 are held together by the aluminum ferrule 16, said aluminum ferrule compressing the cork gasket 52 between the 15 flanges 14 and 15 to form a liquid-tight connection.

The casing 13 is provided with a lower opening 17, the upper part of which is provided with the spherical depression 19 above the groove 18, 20 said depression 19 serving as a valve seat to cooperate with the spherical surface 20 on the valve member V.

The valve member V, as indicated at 25, projects downwardly past the conical valve seat 19 into the opening 17 and is slightly flattened during the course of manufacture (see Fig. 9). The lower portions of the fins are cut off substantially above the bottom 26, as indicated at 27 (see Figs. 1 and 6), so that they will clear the valve seat 19.

As shown in Fig. 3, the fins 23 form the flow passages 28, which permit ready egress of liquid from the mouth 10 of the bottle B past the valve body V, when the valve is lifted from its seat 19.

The upper portions of the fins 23 of the valve body 22, are also cut off below the top of the valve body 22, as shown at 29 in Figs. 1 and 6. Onto the upper portion of the cup 22 is placed the lower contact element 30 for locking ball 31.

40 The contact element 30 is glazed to the top of the valve member V. The sides or edges of the disk member 30 extend beyond the body 22 as shown in Figs. 1 and 9.

The ball contact member 39 is suitably shaped 45 to cause the ball 31, as shown in Fig. 1, to roll to the outside of the casing 12 against the interior wall of the middle or intermediate chamber 35 when the bottle is upright.

Although a curved conical surface 36 is shown, 50 it is understood that other similar types of surfaces may be employed for causing the ball to roll toward the wall of the middle chamber 35 of the casing 12.

As shown in Figs. 1 and 2 in the upper chamber 37 of the casing 12 is positioned the concave 55 upper ball contact member 38 with the cavity 40 having the radial ribs 45, which contact member is preferably ceramically united with the symmetrically positioned angular fins 39 of the casing 12.

The concavity or depression 40 of the element 38 is adapted to receive the ball 31 when the casing 12 is inverted with the bottle B.

When the bottle is in normal upright position, 65 as shown in Fig. 1, the ball 31 will be diverted to the outside of the chamber 35 by the cone peak 36 so that the ball 31 will fall or roll along the slope of the upper contact member of the cone peak 36 of the lower contact member 38 to below the lower portion 41 of the member 38.

As indicated in Fig. 2, the fins 39 will form 75 the flow passages 42, symmetrically positioned around the periphery of the chamber 37. These flow passages 42 will cooperate with the flow pas-

sages 28 of Fig. 3 to permit liquid to flow past the valve 21 and the contact member 38.

The casing element 12 is provided with a center opening 50 which cooperates with the passages 42 past the member 38 and the passages 28 past the valve member V and with the opening 17 in the lower part of the casing 12, whereby liquid may be poured out of the inverted bottle B, when the valve V is lifted from its seat 19.

In operation, when the bottle is in upright 10 position or is in horizontal position, the ball 31 will fall from the cone peak 36 to the side of the chamber 35, contacting with the interior wall thereof, as indicated at Fig. 1.

When the ball 31 moves to the side of the 15 chamber 35, it will position itself between the lower portion 41 of the upper contact member 38 and the outside of the lower contact member 30 and will force the valve 22 against its seat 19, preventing flow of liquid reversely from the opening 50 and through the opening 17 into the bottle 20 10, so that the bottle cannot be refilled.

When the bottle has been turned so that its mouth is inclined downwardly with an inclination substantially below horizontal, approaching 25 the vertical, the ball 31 will roll or slide into the concavity 40. This will permit the valve 22 to move from its seat 19 under the pressure of liquid in the bottle B, whereby a ready exit of liquor may take place through the opening 17, the passages 28 and 42 and the opening 50.

The upper face of the lower ball contact member 30 may also be shaped in other manners than shown to cooperate with the ball 31 and the concavity of the depression 40.

In any case, at the axis 51, there would be a vertical spacing between the uppermost portion of the peak 36 and the uppermost portion of the depression 40, greater than the maximum diameter of the ball. Toward the walls of the chamber 40 35 this spacing should decrease so that the ball will have substantially no clearance as it moves under the influence of gravity along the peaked surface 36 toward the exterior of the chamber 35 and away from the axis 51.

The present construction is particularly advantageous inasmuch as it is possible to make the valve member V of a ceramic material. By firing the elements 12, 38 and 13 assembled as shown in Fig. 8, with a glaze at 65 and without a glaze 50 at 66, the expense of construction is materially decreased. The valve member V is fired as shown in Fig. 9 with a glaze at 67, the bottom 26 becoming flattened during the firing period.

The recesses 130, shown in Figs. 1 and 4, 55 operate with the recesses 131, shown in Figs. 1 and 5, to permit suitable tools to be applied to the casing member 13 and to the valve member V, whereby the seats 19 and 20 may be ground together.

The outer surface of the casing 12 is preferably glazed, but the other surfaces are preferably unglazed.

After the lower ball contact element 30 has been substantially integrally united with the valve body 22 by the firing operation, the valve will be slightly porous.

To prevent any air from escaping from the interior of the valve body, and also to prevent any liquid from entering the valve body, maintaining its buoyancy, it is desirable to impregnate the valve body 22 after the firing operation with a suitable other water-proofing material, which will not be soluble or affected by any liquids which may be received in the bottle 10.

Referring to the upper valve contact element 41, the button 134 serves as a convenient means of centering the element 41 upon the ribs 39, and the ribs 45 in the cavity 40 prevent the ball from being adhesively connected to the cavity 40 when it is wet. The fact that the ball is not wedged, shown in Fig. 1, may be readily demonstrated by the fact that the ball can freely move around the peak of the lower contact element 30, without, however, permitting the valve 21 to be moved from its seat.

As indicated in Figs. 1 and 2 at 135, the exterior of the valve body 12 is preferably provided with a series of indentations or protrusions which enable the body to be conveniently gripped by a tool when the aluminum ferrule 16 is put into position.

The above construction is generally described in the copending application Ser. No. 742,692, filed September 4, 1934.

The present invention is particularly directed to the modification of the construction of said copending application so as to relieve internal vacuums, which may draw the valve V so tightly against the seat 19 as to prevent pouring when the bottle B is inverted.

The vent or leak openings 200 (see Fig. 7) are provided in the lower nipple member 13 to permit air to enter the bottle B when a vacuum is formed therein due to condensation, contraction or cooling of the vapors above the liquid level.

The breathing openings 200 as shown in Figs. 1 and 7 may be formed in the plastic ceramic material, before firing, by inserting thin flexible needles having diameters of less than 0.01 and preferably about 0.006, 0.0065, 0.007 and 0.0075 inch, the openings being of jagged formation as shown in Fig. 7 due to bending or turning of the very thin needles when they encounter hard particles in the plastic molded material.

After firing, the holes will shrink, slightly restricting the opening therethrough and the final channel of the opening 200 will be of such a nature as to permit the vacuum to suck in air but as to prevent the liquid passing therethrough with sufficient force as to enable any substantial entrance of liquid into the bottle past the valve.

In any case, an attempt to introduce spirituous liquors would result in the clogging of such passageway by the various materials in colloidal suspension in such spirituous liquors.

It is thus seen that the applicant has provided an improved nonrefillable bottle closure which, while it prevents creation of a vacuum by by-passage of air around the valve, nevertheless prevents introduction of liquid by such by-passage.

It will thus be seen that there is herein described an apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawing shall be interpreted as illustrative and not in a limiting sense.

What is claimed is:

A non-refillable closure for bottles and containers to receive alcoholic beverages and spirituous liquors, said closure consisting of a substantially cylindrical ceramic casing having a nipple portion projecting inside of the bottle or container and having openings at the ends thereof to permit dispensing of liquid from the container, said casing including a valve to permit flow of liquid from the bottle when the bottle is inverted and to prevent flow when the bottle is upright, said valve being provided with a valve seat which is formed in said casing and with a locking device included in said casing, and said nipple of said casing being provided with a plurality of capillary passages extending in curved lines through the sides of said nipple and beyond said valve seat to permit venting of the atmosphere within said bottle or container, but to prevent substantial passage of liquid.

GILBERT JACKSON. 45
JOSEPH F. MAHER.
